UNITED STATES PATENT OFFICE.

WARNER HILL CAMP, OF ATLANTA, GEORGIA.

INTERNAL-COMBUSTION ENGINE.

1,107,754.

Specification of Letters Patent. Patented Aug. 18, 1914.

Application filed August 31, 1912. Serial No. 718,129.

To all whom it may concern:

Be it known that I, WARNER H. CAMP, a citizen of the United States, residing at Atlanta, in the county of Fulton and State of Georgia, have invented certain new and useful Improvements in Internal-Combustion Engines, of which the following is a specification, reference being had to the accompanying drawings.

10 This invention comprehends new and useful improvements in internal combustion engines, and relates to that class of gas engines which have provided within the cylinders thereof a valve sleeve provided with a series of ports which are brought into communication with corresponding ports formed within the cylinder, thereby providing for admission of the combustible vapors to the communicate alternately with the exhaust 20 the products of combustion.

One of the principal objects of the many which are readily apparent from the present invention to those skilled within the art, is to provide a cylinder with a vacuum chamber in which the valve sleeve operates and reciprocates, whereby the valve sleeve will be caused to return to its uppermost position and also to construct this valve sleeve so that the pressure of compression and explosion within the cylinder will cause it to descend, so that the exhaust and intake ports, respectively may be quickly and readily operated.

Another object of the present invention is 35 to provide a valve sleeve for an engine of the above character having a large port area therein extending around the circumference of the sleeve which is adapted to register with the intake and exhaust ports formed 40 within the cylinder of the engine, which are substantially of large area, so that upon a small reciprocatory movement of the valve sleeve, the ports in the said sleeve will fully communicate alternately with the exhaust 45 and intake ports of the cylinder.

A further object of the invention resides in providing cylinders which are properly water-jacketed so as to provide uniform expansion throughout the same and another 50 object is to provide separable sleeves which are spaced one from the other and which reinforce the cylinder frame against internal pressure strain.

A still further object of the invention is 55 to provide a valve sleeve which has the bore thereof slightly enlarged at the one end and provided with ports which are adapted for

registration with the intake and exhaust ports of the cylinder and still another object of the invention resides in the provision of a water cooled ring which depends within the cylinder for the protection of the ports formed within the sleeves against the heat caused by explosions in said cylinder.

With these and other objects in view the invention consists in the improved construction and novel arrangement and combination of parts, which will be hereinafter fully described, and particularly pointed out in the claims.

In the accompanying drawings has been illustrated a simple and preferred form of the invention, it being however, understood that no limitation is necessarily made to the precise structural details therein exhibited, but that the right is reserved to any changes, alterations, and modifications to which recourse may be had within the scope of the invention and without departing from the spirit or sacrificing the efficiency of the same.

In the said drawings, Figure 1 is a vertical section taken through one cylinder of the engine embodying my invention. Fig. 2 is a similar section taken at right angles to Fig. 1. Fig. 3 is a horizontal section taken on the line 3-3 of Fig. 1. Fig. 4 is a similar section taken on the line 4-4 of Fig. 1. Fig. 5 is a similar section taken on the line 5-5 of Fig. 1. Fig. 6 is another horizontal section taken on the line 6-6 of Fig. 1. Fig. 7 is a plan view of the cam ring and the gearing operatively connected thereto. Fig. 8 is a detail section through the casing illustrating the cam ring in elevation. Fig. 9 is a diagrammatic view of one side of the cam track. Fig. 10 is a detail sectional view taken through the crank shaft casing, and Figs. 11 to 17 are diametric illustrations as to the position of the valve sleeve within one cylinder during the operation of the engine.

In the accompanying drawing forming a part of the subject matter of the present invention, corresponding parts are illustrated by like numerals throughout the several views.

The crank shaft casing, indicated by the numeral 1, is adapted to be supported upon a support in the usual manner, and an oil channel 2 is formed in the bottom of the crank case. A strainer 3, however, is disposed over the channel, so that the oil passing to the latter will be filtered before re-

turning to the tank. Formed within the casing adjacent the upper extremity thereof is an annular flange 4 forming a recess 5, for a purpose which will be hereinafter described, and extending through the crank shaft casing is the usual crank shaft 6.

The cylinder casing supported upon the crank shaft casing 1 comprises an inner member 7 which is cast from one integral piece of material, and provided with recesses or channels 8 to form a suitable water jacket. A cylinder head 9 also has channels 10 extending through the same which communicate with the recesses or channels 8, formed within the main body portion of the casing and thus a complete water circuit is provided. This cylinder head is detachably secured to the body portion of the cylinder by means of stud bolts 11.

The inner portion 7 of the cylinder casing is practically entirely inclosed by an inner sleeve 12, and an outer sleeve 13. This inner sleeve 12 is made of a particular metal which will withstand the constant wear of the various parts thereon and thus increase the general durability thereof. The outer periphery of the inner member 7 is corrugated as at 14, and in the manufacture of this casing, the outer sleeve 13 is placed thereupon in a heated state and as the same cools, it will shrink upon the outer portion of the inner member 7 thereby making a desirable construction which will increase the life of the cylinder and also strengthen the same.

An intake chamber 15 is formed within the cylinder casing and completely encircles the same and is in communication with the intake manifold 16 of the engine by means of a thimble 17. The inner sleeve 12 of the cylinder casing is provided with a plurality of openings 18 communicating with the combustion chamber thereof and which extend around said sleeve for the greater portion of the circumference of the same to provide intake ports for communication with the intake port of the cylinder. An exhaust chamber 19 encircles the cylinder casing and is also in communication with an exhaust manifold 20 by means of a thimble 21, and the sleeve 12 is provided with a plurality of exhaust openings 22 which are in communication with the upper extremity of the exhaust chamber 19. These intake and exhaust ports practically encircle the entire circumference of the combustion chamber to insure absolute symmetry and that portion of the sleeve 12 between the series of ports 18 and 22 is indicated as 23 at which point the opening formed within the valve sleeve registers during the explosion of the engine, which will be hereinafter described, and this ring is properly water jacketed, as shown for a purpose which is obvious.

The valve sleeve, indicated by the nu-

meral 24, is slidably and rotatably mounted within the inner sleeve 12 of the cylinder casing and has its upper extremity bored to an increased diameter 25 which operates within a vacuum chamber 26, formed between the inner sleeve 12 and the cylinder head 9. This valve sleeve is provided adjacent the lower extremity of the increased diameter portion thereof, with a plurality of ports 27 which are adapted to register with the intake and exhaust ports of the cylinder casing. A piston 28 is mounted to reciprocate within the valve sleeve and is connected to the crank shaft of the engine by means of the pitman rod 29, in the usual manner. This valve sleeve is provided with an annular flange 30 and an adjustable flange 31 between which is adjustably mounted a cam ring 32 which is designed to rotate on the sleeve 24 within the recess 5 formed within the upper extremity of the crank shaft casing, and the flange 4 forms a guide for the lower end of the valve sleeve. This cam ring 32 is provided with a groove 33 in which travel conical shaped rollers 34, which are adjustably mounted within the upper extremity of the crank shaft casing and arranged diametrically opposite. These cone shaped rollers operate within the cam groove 33, insuring proper reciprocation of the valve sleeve during the rotation of the cam ring 32 on said sleeve, and to provide means for rotating this cam ring 32, I provide mechanism which is in operative connection with the crank shaft 100 of the engine. This mechanism comprises a beveled gear 35 which is keyed to the crank shaft of the engine and which is in mesh with the beveled gear 36 keyed upon the lower extremity of a vertically extending shaft 37 journaled within the crank shaft casing. The outer periphery of the cam ring 32 is provided with gear teeth 38 which are in mesh with a pinion 39 keyed upon the upper extremity of the shaft 37, 110 whereby upon the rotation of the crank shaft, a rotary movement will also be imparted to the cam ring on the valve sleeve. This connection between the crank shaft and the cam ring is a four to one connection, that is, upon four revolutions of the gear wheel 39, the cam ring will be rotated but once and the valve sleeve will be moved slightly in accordance therewith. It must be here stated that the cam ring is rotatable on the lower end of the sleeve 24, independent of the latter and primarily for the purpose of controlling the reciprocation of the same, but said sleeve is capable of rotation in the cylinder casing and at times is given a partial rotation in view of the slight friction between said cam ring and the members 30 and 31, between which said cam ring is disposed.

The cylinder head 9 is provided with a

depending annular and hollow flange 40 which is suitably water jacketed, and which is supported by the cylinder head by means of apertured bosses 41, preferably three in number, as shown in Fig. 3 of the drawing. The openings formed in said bosses extend completely therethrough and afford communication between the interior of the annular flange 40 and the water chamber of the cylinder head, thereby producing an explosion chamber which is properly water jacketed to insure cooling. The openings 45 formed between the said bosses 41 provide a passageway communicating the intake chamber with the explosion chamber of the cylinder. This cylinder head 9 is provided with the usual spark plug 42 and is completely covered by a gasing 43 which forms a continuation of the outer sleeve 13 of the cylinder casing to give the engine a neat appearance, and this casing is also provided with an insulated opening 44 through which the wires of the circuit in which the spark plug is included may extend. This cylinder head 35 is provided with outer packing rings 44' which contact with the walls of the cylinder casing to insure an air tight covering for the vacuum chamber 26. An apertured bolt 45 is adjustably mounted within a recess 46 formed within the cylinder head and the said recess is in communication with the upper extremity of the vacuum chamber by means of a passageway 47. This will obviously provide means for the escape of any gas or oil which should accumulate within the vacuum chamber and a spring actuated valve 48 is mounted within the recess 46 to prevent any air from entering the vacuum chamber during the downward stroke of the valve sleeve.

It is apparent from the foregoing that when the explosion takes place within the cylinder, the same will act upon the beveled edge 49 formed upon the interior of the valve sleeve and force the same downwardly and the vacuum then created within the chamber 26 will apparently counterbalance the valve sleeve and have a tendency to return the same to its normal or raised position, and the cam ring 32 will obviously, through the mechanism before described, impart a uniform reciprocal movement of the valve sleeve to insure proper timing of the same. The adjustable flange 31, mounted upon the lower extremity of the valve sleeve, is provided with a split portion 50 through which extends a set screw to provide a locking means for holding the said ring in place, thus providing a means for locking said ring in any adjusted position and particularly for the purpose of taking up any lost motion between the ring member and sleeve.

A water manifold 51 is in communication with the water passageway formed within the cylinder jacket by means of a sleeve 52.

To properly lubricate the valve sleeve and timing mechanism, I provide within the cylinder casing communicating arteries or passageways which are in communication with an oil manifold 53, whereby the oil may be forced around the valve sleeve by means of a pump in any well known or preferred manner. The inner member 7 of the cylinder casing is provided with a pair of circular passageways 54, which are in communication by a vertical passageway 55 and the last mentioned passageway being in communication with the oil manifold, as shown. The medial portion of the periphery of the valve sleeve is provided with a spirally arranged oil groove 55' which is in communication with the passageway 54 by means of openings 56 extending through the inner sleeve 12 of the cylinder casing. This will apparently provide a suitable oil supply to the outer periphery of the sleeve valve to insure a uniform operation of the same. A semi-circular passageway 57 is formed within the upper extremity of the cylinder casing and is also in communication with an oil groove 58 formed within the outer periphery and adjacent the upper extremity of the valve sleeve to provide means for lubricating the upper extremity of the sleeve during the operation thereof. The lower circular passageways 54 are in communication with the crank case by means of a passageway 59 whereby the oil may exhaust into the lower extremity of the crank casing and discharges through the passageway 2.

It is obvious from the foregoing that the sub-*a* inospheric pressure or vacuum in the vacuum chamber operates on the extreme upper end of the valve sleeve and assists in drawing the valve sleeve toward the head of the cylinder and thereby opens the intake port, this taking place during the stroke immediately following the exhaust. In this connection, reference should be had to the diametric illustrations as shown in Figs. 11 to 17 of the drawing and taken in connection with the diagrammatic illustration of the cam groove, as shown in Fig. 9 of the drawing. When the valve sleeve is at its uppermost position, it will be in the position as shown in Figs. 1, 2 and 12 of the drawing, and upon the next down stroke of the piston, the charge of gas will be drawn, therein through the intake openings, as shown upon 120 the next stroke of the piston, as illustrated in Fig. 13 of the drawing. During the aforesaid stroke of the piston, the cam ring is in continual rotation through the mechanism before described and the rollers 34 will 125 travel within the cam groove at a distance equal to A B, as shown in Fig. 9 of the drawing, thereby also insuring proper reciprocation of the valve sleeve to bring the ports formed within the valve sleeve out of 130

alinement with the intake ports of the cylinder casing, thereby cutting off all communication between the combustion chamber of the cylinder and the inlet and outlet ports.

5 Upon the next upward stroke of the piston, as shown in Fig. 14 of the drawing, the gases contained within the cylinder will be compressed and the compressed gas acts on the counter-bore of the valve sleeve to shift 70 the same downwardly and outwardly, thereby acting against the vacuum contained within the vacuum chamber at upper end of valve sleeve and still closing the communication between the ports of the casing and 75 the combustion chamber. When the piston is traveling upon this up stroke, the cam ring will also travel the distance from B to C, as illustrated in Fig. 9 of the drawing thereby properly controlling the operation 80 of the valve sleeve. When the piston is in its second uppermost position, the ignition takes place within the cylinder and obviously forces the piston downwardly, as shown in Figs. 14 and 15 of the drawing, and when 85 this ignition occurs, pressure (additional to piston compression) within the combustion chamber acts with sufficient force on the counterbore of the sleeve to shift the same downwardly thereby causing the ports contained within the valve sleeve to register 90 with the exhaust ports of the cylinder casing and permitting the gases within the combustion chamber to exhaust therethrough. During this downward or working operation 95 of the piston, the cam ring will travel the distance from C to D, and E as illustrated in Fig. 9 of the drawing, and owing to this inclined portion of the cam groove, it will also insure the proper operation of 100 the sleeve, bringing the same in alinement 105 with the exhaust ports of the cylinder casing. Upon the next upward stroke of the piston, the vacuum contained within the vacuum chamber will cause the valve sleeve to ascend as the pressure within the combustion chamber is exhausted and the cam ring will travel the distance from E to F, thereby preventing the valve sleeve from 110 assuming its uppermost position but at a position where the ports contained within the 115 valve sleeve will be in alinement with the ring 23, thereby cutting off all communication between the ports of the cylinder and the combustion chamber. The cam ring then 120 travels the distance from F to G, thus permitting the valve sleeve to ascend to its uppermost position and bringing the ports contained within the sleeve into alinement with the intake ports of the cylinder, thereby permitting 125 the gases to be brought into the cylinder upon the suction of the next down stroke of the piston. It is apparent that the sub-atmospheric pressure or vacuum contained within the vacuum chamber has a 130 tendency to hold the valve sleeve in its upper,

most position, but the compression within the cylinder overcomes the action of the vacuum, thereby causing the valve sleeve to descend and the cam ring with its mechanism as before described serves to insure proper position of the valve sleeve to properly control 79 its movements.

In Fig. 9 of the drawing, I have only illustrated one half of the cam groove 33 formed within the cam ring but it is of course, obvious that the other half of the cam groove will extend in an opposite direction from that portion of the cam groove as shown, so that the rollers 34 will be arranged diametrically opposite within the casing 80 and act jointly during the rotation of the cam ring so that upon one complete revolution of said ring, the crank shaft will have made four revolutions and obviously two explosions within the cylinders of the engine will take place during a single rotation 85 of the cam ring.

It will be manifest from the foregoing that an internal combustion engine of this character will be simple, durable and strong 90 when in use, the parts of which may be cheaply manufactured and readily assembled and installed, and which will require practically no attention to maintain the proper running order thereof.

Having thus described my invention, what I claim is:—

1. In an internal combustion engine, the combination of a cylinder having a combustion chamber, said cylinder being provided with intake and exhaust ports and having a vacuum chamber formed therein, a piston operative in the cylinder, and a valve sleeve capable of reciprocation in the cylinder to control the intake and exhaust ports thereof, 100 such sleeve having a portion subject to the action of vacuum in the vacuum chamber to cause reciprocation of the sleeve in one direction and also a portion subject to the compression in the combustion chamber to cause 105 reciprocation of the sleeve in a reverse direction.

2. In an internal combustion engine, the combination of a cylinder having a combustion chamber, said cylinder being provided 110 with intake and exhaust ports and having a vacuum chamber formed therein, a piston operative in the cylinder, and a reciprocable valve sleeve controlling said ports, such sleeve having a portion thereof subject to 115 the action of vacuum in the vacuum chamber to cause reciprocation of the sleeve in a direction to open the intake port and having a portion subject to the pressure of explosion in the combustion chamber to cause 120 reciprocation of the sleeve in a reverse direction to open the exhaust port.

3. In an internal combustion engine, the combination of a cylinder having a combustion chamber, said cylinder being provided 125

- with intake and exhaust ports and having a vacuum chamber formed therein, a piston operative in the cylinder, and a reciprocatory valve sleeve in the cylinder for controlling the intake and exhaust ports, such sleeve having a portion thereof subject to the action of vacuum in the vacuum chamber to cause reciprocation of the sleeve in a direction to open the intake port and another portion subject successively to the compression and explosion pressures in the combustion chamber to reciprocate the sleeve in a reverse direction to close the intake port and subsequently open the exhaust port.
4. In a gas engine of the type described, the combination of a cylinder casing, a valve sleeve reciprocably mounted therein, a cam ring rotatably mounted upon said valve sleeve, and means in operative connection with said cam ring for controlling the proper reciprocation of said sleeve, said valve sleeve being also capable of a slight rotary movement through the operation of the last mentioned means.
5. In an internal combustion engine of the four cycle type, the combination of a cylinder casing, of a valve sleeve rotatably and reciprocably mounted therein, a cam ring rotatably mounted upon said valve sleeve, rollers adjustably mounted within said casing and operative within a groove formed within said cam ring, and means for rotating positively, the cam ring for insuring proper rotation and reciprocation of the valve sleeve.
6. In an internal combustion engine of the four cycle type, the combination of a cylinder casing, a valve sleeve operatively mounted therein, a crank case in connection with said casing, a crank shaft mounted within said crank case, a piston reciprocably mounted within said valve sleeve and in operative connection with said crank shaft, a ring mounted upon said valve sleeve and having a cam groove formed therein, means in operative connection with said ring for positively rotating said ring and rollers operative within said cam groove for controlling the proper reciprocation of said ring and valve sleeve, substantially as described.
7. In an internal combustion engine of the four cycle type, the combination of a cylinder casing, a cylinder head mounted thereupon and depending within said casing, a portion of the depending part of said head being spaced from the wall of the cylinder to provide a vacuum chamber therebetween, a valve sleeve reciprocably mounted within said cylinder casing and having an extension of increased inside diameter extending within said vacuum chamber, means for controlling the reciprocation of said sleeve, the compression on said cylinder casing and the vacuum in said chamber assisting, respectively, in the downward and upward movement of said valve sleeve.
8. In a four cycle internal combustion engine, the combination of a cylinder casing, of a cylinder head mounted thereupon, and having a portion depending within the cylinder casing, a portion of the depending part of said head being spaced from the wall of the cylinder to provide a vacuum chamber therebetween, a valve sleeve operatively mounted within said cylinder casing and projecting in said vacuum chamber, said cylinder head having a passageway formed therein communicating said vacuum chamber with the atmosphere and a spring actuated valve mounted within said passageway, substantially as and for the purpose specified.
9. In an internal combustion engine of the four cycle type, the combination of a crank shaft casing, an annular flange extending within the same, a cylinder casing mounted upon the crank shaft casing, a valve sleeve mounted within said casings, a cam ring mounted upon the said valve sleeve and operatively mounted between said annular flange and said cylinder casing, means for rotating and reciprocating said cam ring for insuring the proper operation of said valve sleeve, substantially as described.
10. In an internal combustion engine of the class described, a cylinder, a cylinder head mounted thereon, said head being provided with a water-cooled depending portion arranged in spaced relation to the inner wall of the cylinder to provide an annular vacuum chamber therebetween, intake and exhaust ports provided in connection with the cylinder, a piston operatively mounted in said cylinder, and a reciprocal valve sleeve mounted in the cylinder between the inner wall thereof and said piston, the upper end of said sleeve being increased in diameter to fit snugly in the aforesaid annular vacuum chamber, whereby to cause the reciprocation of the sleeve in a direction to open the intake port, the remaining portions of said valve sleeve being subject successively to the compression and explosion pressures in the cylinder to reciprocate said sleeve in a reverse direction, whereby to close the intake port and subsequently open the exhaust port.
- In testimony whereof I hereunto affix my signature in the presence of two witnesses.
